Primary Examiner — Calvin E Vansant*Assistant Examiner* — Sydney M Evans(74) *Attorney, Agent, or Firm* — Marshall & Melhorn, LLC(57) **CLAIM**

The ornamental design for a flange as shown and described.

DESCRIPTION

FIG. 1 is a top perspective view of an embodiment of a flange showing our new design;

FIG. 2 is a bottom perspective view thereof;

FIG. 3 is a first side view thereof;

FIG. 4 is a second side view thereof;

FIG. 5 is a top view thereof;

FIG. 6 is a bottom view thereof;

FIG. 7 is a third side view thereof; and,

FIG. 8 is a fourth side view thereof.

The broken lines in the drawings are included to show portions of the flange that form no part of the claimed design.

1 Claim, 3 Drawing Sheets
